UNITED STATES PATENT OFFICE.

PETER T. COFFIELD, OF DAYTON, OHIO.

MEANS FOR IMPARTING ROTARY RECIPROCATING MOTION.

No. 853,440.

Specification of Letters Patent.

Patented May 14, 1907.

Application filed September 26, 1906. Serial No. 336,366.

To all whom it may concern:

Be it known that I, PETER T. COFFIELD, a citizen of the United States, residing at Dayton, in the county of Montgomery and State 5 of Ohio, have invented certain new and useful Improvements in Means for Imparting Rotary Reciprocating Motion to Washing-Machines; and I do declare the following to be a full, clear, and exact description of the 10 invention, such as will enable others skilled in the art to which it appertains to make and use the same, reference being had to the accompanying drawings, and to the letters and figures of reference marked thereon, which 15 form a part of this specification.

This invention relates to means for imparting rotary-reciprocating motion to a tub or receptacle, such for example, as a washing machine, during the operation of washing 20 clothes. The motion is transmitted to the tub or receptacle from any desirable source of power, such for example, as a motor, and the intervening mechanism between the motor, and the receptacle or tub comprises the 25 invention.

The object of said invention is to provide means for transmitting the motion from the motor to the tub or vessel and to relieve the motor mechanism of the sudden jars or strain 30 incident to the reversal of the movement of said tub or receptacle. It will be understood that the weight of the tub or receptacle due to the contents therein, increases the strain or jar when motion is reversed, to a 35 great extent, and that in order to relieve the driving mechanism of such strain, the proper mechanism is provided which will allow a continued limited movement of the tub or vessel due to momentum, after the driving 40 mechanism has reached the limit of its movement in the reverse directions. In other words, the tub or vessel has some independent motion after the driving mechanism has reached the limit of its movement, and 45 owing to this continued movement of the vessel or tub, the driving mechanism must be relieved of the strain incidental thereto.

Preceding a more detailed description of the invention, reference is made to the accompanying drawings, of which—

Figure 1, is a side elevation of the apparatus complete, parts of the frame-work being shown in section. Fig. 2, is an enlarged plan view of a part of the apparatus with the tub 55 or receptacle removed. Fig. 3, is a detailed view of the lock socket connection through

which the tub or receptacle is connected with the motor gearing, and through which the tub may have continued movement due to momentum. Fig. 4, is a vertical sectional view on the line x—x of Fig. 2.

In a detail description of the invention, similar reference characters indicate corresponding parts.

A suitable water motor 1 is utilized to furnish the driving power. The construction of the motor does not enter into the present invention, therefore, it will not be described in detail. Such water motor may receive its supply from any suitable source, such as the city water works. The piston rod 2 of the motor carries on its outer end a rack 3 which meshes with a gear wheel 4 of suitable diameter which it drives; this gear wheel 4 turns loosely on an upright shaft 5 and rests upon a bearing or standard 6, the latter being supported in the frame-work of the apparatus. Rigidly secured to the upper face of the gear wheel 4 is a bracket consisting of two arms 7—7 extending from a hub 8 and terminating in upright portions; the hub 8 contains an aperture through which the shaft 5 extends; said shaft turns loosely in said hub. The said shaft 5 also extends loosely through a portion of the frame-work 10 which constitutes a bearing for maintaining it in a true perpendicular position; the shaft thence extends through a hub 16 to which it is secured by a pin 15; extending from this hub 16 is a series of arms 17, the whole constituting a spider which is attached to the bottom of the tub or receptacle 18 and in the center of the same. Rigidly attached upon the upper side of the cross frame 10 is a stationary bearing 11 between which and the lower end of the hub 16 there is a ball bearing 13 inclosed between suitable hard steel plates attached to the parts 11 and 16.

Connected at one end to each of the arms 7—7 are spiral springs 14 which extend inwardly to fit over trunnions 12 projecting from opposite sides of a clutch ring 19. The interior projections 20 of this clutch interlock with the opposite recessed sides of the spider hub 16, so that movement is imparted to the tub or receptacle through this clutch from the bracket arms 7—7; the hub bearing upon the ball bearing 13—13. As will be seen from Fig. 4, the clutch ring 19 rests upon the upper surface of the bearing piece 11. The wash tub or receptacle 18 is rotated from the arms 7—7, which, as before

stated, move with the gear wheel 4. The springs 14—14 attached to said arms are closed that is to say, they are formed of closed coils sufficiently strong to act as power arms through which motion is transmitted to the clutch ring 19 and thence to the wash tub or receptacle.

The momentum of the tub 18, after the driving rack 3 has reached its limit in either direction, will have the effect of continuing the rotation of said receptacle; in order to relieve the power-transmitting devices of the strain due to the force of this momentum, the spiral springs 14—14 serve as yielding stops to receive the strain due to such momentum. These springs will expand and will move out of the true line at such times, as is shown in Fig. 2, and will thus relieve the driving mechanism of the strain. In other words, when the limit of movement in either direction, of the gear wheel 4 and arms 7—7 is reached, the springs 14—14 will be directly acted upon to yieldingly stop the momentum of the tub.

25 The operation of the apparatus is briefly described as follows: Water is admitted to the motor under pressure to drive the piston and to impart reciprocating movement to the rack 3 through the intervening piston rod 2; the rack imparts similar movement to the tub or vessel 18 through the arms 7 which are united to the spur wheel 4 and the springs 14, which are connected to the projections 20 of the clutch ring 19, said clutch interlocking 35 with the spider hub 16.

I claim as my invention:

1. In means for imparting rotary-reciprocating motion to a receptacle such as a washing machine, the combination, of a spider attached to the bottom of said receptacle, a bearing for the hub of said spider, a clutch engaging said hub, a driving gear, a bracket extending from said driving gear, and resilient connections between said bracket and said clutch, whereby movement is imparted to said receptacle, and means for rotating said gear wheel in opposite directions.

2. In means for imparting rotary-reciprocating motion to a receptacle such as a washing machine, the combination, of a driving gear, means for imparting rotary-reciprocating movement to said gear, a bracket fixed to and extending from said gear, and connections between said bracket and said receptacle comprising a hub upon which the receptacle

is supported, a clutch engaging said hub, and spiral springs engaging said clutch and the bracket extending from the driving gear.

3. In means for imparting rotary-reciprocating motion to a receptacle such as a washing machine, the combination, of a driving gear, means for imparting rotary-reciprocating motion to said gear, a hub upon which said receptacle is mounted, and resilient connections, a bracket extending from the driving gear and said hub, said resilient connections being between said bracket and said hub, whereby means are provided for imparting to the receptacle movement similar to those of the driving gear, and for permitting further movement of the receptacle due to the momentum thereof.

4. In means for imparting rotary-reciprocating motion to a receptacle such as a washing machine, the combination, of a hub attached to the bottom of said receptacle, an anti-friction bearing for said hub, a clutch ring interlocked with said hub, a driving gear, means for imparting rotary-reciprocating movement to said gear, bracket arms extending from said gear, and resilient connections between said bracket arms and the clutch ring, whereby means are provided for imparting to the receptacle movement similar to that of the driving gear, and for permitting the additional movement of said receptacle due to the momentum thereof.

5. In means for imparting rotary-reciprocating movement to a receptacle such as a washing machine, the combination, of an anti-friction bearing for said hub, a clutch ring interlocked with said hub, a shaft pinned to said hub, a driving gear, a bracket attached to said driving gear and into which said shaft is loosely projected, means for imparting to said gear rotary-reciprocating movement, and spiral springs connecting the clutch ring at opposite sides to said bracket, whereby movement is imparted to said receptacle similar to that of the driving gear, and means are provided for allowing further movement of the receptacle due to the momentum thereof.

In testimony whereof I affix my signature, in presence of two witnesses.

PETER T. COFFIELD.
